United States Patent Office

Des. 179,563

Patented Jan. 22, 1957

179,563

ELECTRIC SHAVER

Robert O. Ernest, Oak Park, Ill., assignor to Sunbeam Corporation, Chicago, Ill., a corporation of Illinois

Application September 13, 1955, Serial No. 37,907

Term of patent 14 years

(Cl. D22—3)

Fig. 1.

Fig. 2.

Fig. 3.

Fig. 4.

Fig. 1 is a perspective view of an electric shaver embodying my new design;

Fig. 2 is a side elevational view of the electric shaver of Fig. 1;

Fig. 3 is a front elevational view of the electric shaver shown in Fig. 1, the opposite face thereof presenting a similar appearance; and

Fig. 4 is a top plan view thereof.

I claim:

The ornamental design for an electric shaver, substantially as shown and described.
